UNITED STATES PATENT OFFICE.

LAURIER A. MAYNARD, OF DETROIT, MICHIGAN.

MOTOR-OPERATED RAZOR.

Application filed March 13, 1924. Serial No. 699,050.

To all whom it may concern:

Be it known that I, LAURIER A. MAYNARD, a citizen of the United States, residing at Detroit, in the county of Wayne and State 5 of Michigan, have invented certain new and useful Improvements in Motor-Operated Razors, of which the following is a specification, references being had therein to the accompanying drawings.

10 This invention relates to motor operated razors and my invention aims to provide a novel power transmission mechanism by which a razor blade may be rapidly reciprocated from the power provided by an electric motor or other source of power to which the power transmission mechanism is articulated so that the razor may be freely manipulated relative to a face. It is in this connection, that the power transmission 15 mechanism is housed within a handle member of the razor and provision is made whereby easy access may be had to the transmission mechanism for lubricating or repair purposes.

20 My invention further aims to provide a power razor wherein a driven cam is adapted to oscillate crank shafts and cause said shafts to oscillate or reciprocate a razor blade, which is provided with a yieldable 25 guard adapted to contact with the face and crowd the flesh head of the blade so that the flesh will be stretched to facilitating the cutting of hair by the razor blade.

30 My invention will be hereinafter specifically described in the claims, and reference will now be had to the drawing, wherein—

Figure 1 is a side elevation of the razor showing the handle portion thereof in longitudinal section;

Fig. 2 is a plan of the razor partly in section on the line II—II of Fig. 1;

Fig. 3 is a cross sectional view of the razor taken on the line III—III of Fig. 1;

Fig. 4 is a similar view taken on the line IV—IV of Fig. 1;

Fig. 5 is a similar view taken on the line V—V of Fig. 1;

Fig. 6 is a view of the outer end of the 50 razor blade showing the guard;

Fig. 7 is a perspective view of a detached coupling member, and

Fig. 8 is a perspective view of a detached double crank.

55 In the drawing, the reference numeral 1 denotes an oblong handle provided with a

finger ring or hole 2, and said handle is substantially hollow with the upper portion thereof affording a barrel 3 and the lower portion thereof a casing 4, said casing 60 having a detachable side wall 5 that may be held in place by screws 6.

The outer end of the handle or barrel is provided with a detachable screw plug 7 that may be held against accidental rotation by a set screw 8 and in said plug is an anti-frictional bearing 9, in the form of a ball for the enlarged end 10 of a driven cam shaft 11 which is journaled in a bore 12 formed in the inner end of the handle 1. 65 The bore 12 is enlarged to receive a sleeve 13 held in place by a set screw 14 and mounted in the sleeve is the flexible casing 15 of a flexible drive shaft 16 suitably connected to the cam shaft 11, as at 17. The 70 flexible shaft 16 is adapted to be driven from an electric motor or other source of power with the casing 15 of sufficient length to permit of the handle 1 being freely manipulated relative to the source of power. 75

The handle 1 at the bore 12, has an annular recess 18 for anti-frictional bearings 19, preferably balls, against which bear a collar 20 on the cam shaft 11, so that the anti-frictional bearings 19 may cooperate 80 with the bearing 9 in holding the cam shaft against any end thrust or longitudinal movement.

85 Mounted in the detachable side wall 5 and the wall of the casing 4 are transversely disposed parallel shafts 21 and loose on said shafts are double cranks 22, each having a set of crank arms 23 and 24. The arms 23 of both of said double cranks are pivotally connected, by pins 25 to the apertured lugs 90 26 of a two-part coupling member 27 which has its parts connected together by a set screw 28. The parts of the coupling member are formed with recesses 29 for anti-frictional bearings 30 and extending between 95 said anti-frictional bearings is a disk or cam 31 carried by the cam shaft 11. The cam is in the form of a disk set at an angle, other than a right angle, to the cam shaft 11 whereby the disk will serve as a cam when 100 the shaft 11 is driven, thus causing the coupling member 27 to be shifted back and forth to impart a rocking movement to the double cranks 22.

105 The outer end wall of the casing 4 has an opening 32 and extending through said opening into the casing 4 is the shank 33 of a

razor blade 34. The shank 33 is pivotally mounted between the arms 24 of the double cranks 22 by pins 35 and in consequence of this connection the blade 34 may have a 5 reciprocatory movement imparted thereto from the driven cam shaft 11. The blade 34 is of a conventional form that may be stropped, but I equip said blade with a guard 36 disposed parallel to the cutting edge of 10 the blade and adapted to swing to either side of the plane of said blade. The guard is in the form of a rigid piece of wire having its outer end provided with a pintle 37 loosely mounted in a bracket 38 attached to 15 the back of the blade 34 by a set screw 39 or other fastening means.

On the shank 33, adjacent the end of the blade 34 is a strap 40 embracing the shank 33 with inturned lugs 41 extending under 20 the shank and retained in engagement therewith by a bracket 42 and a set screw 43. The strap 40 also has resilient opposed arms 44 between which extends the inner angular pintle end 45 of the guard 36 with the pintle 25 loosely mounted in the bracket 42 which cooperates with the bracket 38 in pivotally supporting the guard so that by pressure it may be swung to that side of the razor blade. The resilient arms 44 hold the guard 36 normally in the plane of the blade 34, as best 30 shown in Figs. 5 and 6, but when the razor blade is placed against the face the guard is swung out of the plane of the blade and is stressed the resilient arm 44 which it 35 engages. This particularly stressed resilient arm will produce a pressure on the guard against the face and consequently as the razor blade is advanced over the face the guard will crown the flesh head of the handle and edge of the razor blade, smoothing 40 out the skin so that the reciprocating blade may readily attack the hair on the face. Assuming that the blade is reasonably sharp it is obvious that its fast motion will cause 45 hairs to be quickly severed and the guard 36 will contribute towards a close shave.

From the foregoing it will be observed that I have housed within the razor handle a compact power transmission mechanism 50 by which a rotary motion may be converted into a reciprocating motion, thus causing the razor blade to be driven and reciprocated from a flexible power shaft. By removing the detachable side wall the mechanism can 55 be lubricated and maintained in an operable condition and since such mechanism is at a point remote from the blade 34 there is no danger of the mechanism becoming unsanitary or interfering with stropping of 60 the razor blade. Then again, the power transmission mechanism is such that the razor blade is not exactly reciprocated in a linear direction but describes an arc which approaches the sweeping action of drawing 65 a razor blade over the face. This is a thing

desired in connection with any power razor for it eliminates what may be considered a direct sawing action and produces more of a drawing movement of the blade against the hair. The blade is oscillated by its connected cranks and my invention in its broadest aspect involves a crank supported blade with means for actuating the cranks to cause oscillation of the blade.

One embodiment of my invention has 75 been illustrated, but it is to be understood that the structural elements are susceptible to such variations and modifications as fall within the scope of the appended claims.

What I claim is:—

1. In a power razor, a handle, a razor blade having a shank extending into said handle, a flexible shaft extending into said handle, and power transmission mechanism in said handle operated from said flexible shaft and adapted to oscillate said razor blade, said power transmission means including a cam shaft, cranks supporting the razor blade shank, and a coupling member articulating said cranks and actuated by said cam shaft.

2. Means for reciprocating a razor blade having a shank, comprising crank shafts supporting the blade by its shank, a coupling member articulating said crank shafts, and means engaging said coupling member to cause oscillation thereof.

3. Razor blade reciprocating means as called for in claim 2, wherein the last mentioned means includes a driven cam shaft.

4. Razor blade reciprocating means as called for in claim 2, wherein said coupling member contains anti-frictional bearings and the last mentioned means extending between said bearings.

5. A power razor comprising a casing, a blade having a shank extending into said casing, a barrel adjoining said casing, a driven cam shaft extending into said barrel, and means in said casing supporting the shank of said blade and actuated from said cam shaft adapted for reciprocating said blade.

6. A power razor as called for in claim 5, wherein said means includes cranks connected by a coupling member actuated by said cam shaft.

7. A power razor comprising a handle, a driven shaft extending into the inner end of said handle, a blade having a shank extending into the outer end of said handle and parallel with said shank, and spaced apart rocking means in said handle solely supporting the blade shank and articulating said shaft and blade shank so that said shaft may cause oscillation of said blade.

8. In a power razor, a handle, a blade having a shank extending into said handle, and power transmission means in said handle articulated with said blade shank for causing

an oscillatory movement of said blade, said power transmission means including double cranks supporting said blade shank.

9. A power razor comprising a handle, a blade having a shank in said handle, a power shaft extending into said handle parallel to the blade shank, a power transmission means between said power shaft and said blade shank to support and guide the movement of the entire blade and shank in similar arcuated paths of like amplitude.

10. A power razor comprising a handle, a blade having a shank in said handle, a

power shank extending into said handle and adapted to transmit power to said blade shank, and means effecting an endwise motion of the blade through an arc with the cutting edge of the blade maintained throughout such movement against endwise tilting.

In testimony whereof I affix my signature in presence of two witnesses.

LAURIER A. MAYNARD.
